UNITED STATES PATENT OFFICE.

RALPH P. CLARKSON, OF WOLFVILLE, NOVA SCOTIA, CANADA, ASSIGNOR TO INTERNATIONAL STREAM FLOW TURBINE COMPANY, LIMITED, OF WOLFVILLE, NOVA SCOTIA, CANADA, A CORPORATION OF NOVA SCOTIA.

HYDRAULIC CURRENT-MOTOR.

1,237,868.

Specification of Letters Patent. Patented Aug. 21, 1917.

Application filed June 19, 1916. Serial No. 104,359.

To all whom it may concern:

Be it known that I, RALPH P. CLARKSON, a citizen of the United States, residing at Wolfville, Province of Nova Scotia, Dominion of Canada, have invented a new and useful Hydraulic Current-Motor, of which the following is a specification.

This invention relates to a hydraulic current motor capable of general application but particularly designed and adapted for use in tidal currents and in navigable rivers where obstruction to the movement of shipping must be avoided.

It is the general object of my invention to provide an improved hydraulic current motor of a type adapted to operate most efficiently when substantially or completely submerged. It is a further object of my invention to embody my improvements in a motor which is essentially self-contained and which requires no extensive preparation of site for its installation. Another object is to provide a current motor which will utilize with high efficiency current flowing in either direction without reversal of the direction of travel of the moving parts of the apparatus.

With these general objects in view, one feature of my invention relates to the provision of a hydraulic current motor comprising stationary members disposed in different horizontal planes, and movable members traveling along a closed path adjacent said stationary members and transversely of the current.

Another feature of my invention, in its preferred form, relates to the provision in a hydraulic current motor of two sets of stationary members and a single set of movable members, said latter members being supported for movement between the two sets of fixed members, and said fixed members being closely adjacent said moving members on each side thereof, and being adjustable in position whereby they are adapted for use as either entrance or discharge members.

In the complete embodiment of my invention I provide stationary members on each side of and closely adjacent to the movable members and positioned in superposed horizontal planes, and I mount the movable members so that they will travel

in a closed path past all of the stationary members successively. The frame of the motor comprises partitions which divide the current in substantially horizontal planes, and the stationary members direct the flow in substantially reverse directions against the movable members as they move in their closed path in different planes thereby.

Further objects of my invention relate to certain arrangements and combinations of parts which will be hereinafter described and more particularly pointed out in the appended claims.

A preferred form of my invention and certain modifications thereof are shown in the drawings in which—

Figure 1 is a diagrammatic plan view of the principal parts of my improved mechanism;

Fig. 2 is a fragmentary plan view showing the position assumed by certain of the parts appearing in Fig. 1, upon reversal of the direction of current flow;

Fig. 3 is a front elevation of a plurality of the movable members or vanes, and of a portion of their supporting mechanism;

Fig. 4 is a perspective view showing a pair of entrance guides, a pair of discharge guides, and a pair of vanes movable between the two sets of stationary guides;

Fig. 5 is a sectional side elevation taken along the line 5—5 in Fig. 1;

Fig. 6 is a perspective view of certain of the stationary guides, looking in the direction of the arrow 6 in Fig. 2;

Fig. 7 is a detail view of one of the rolls for guiding the flexible members which support the movable vanes;

Fig. 8 shows a modified form of support for the flexible members, and

Fig. 9 is a side elevation of one of the movable vanes and shows means for supporting the vane independently of the flexible members.

Referring to the drawings, and particularly to Figs. 5 and 6, it will be seen that my improved current motor in its preferred form is mounted in a rigid frame having three substantially continuous horizontal partitions or planes 10, 11 and 12, spaced apart by suitable supporting members 13. This frame work is shown only in a diagrammatic way and it will be understood

that the proportions of the parts may be varied to provide the necessary strength and rigidity. This rigid frame forms a support for all of the operative parts of the mechanism. The machine, being thus self-contained, may be placed in operation merely by submerging the frame and the mechanism carried thereby in any desired location and by securing it in such a position that the frame will extend transversely of the direction of current flow. It is merely necessary to provide a reasonably smooth bottom and to provide means for securing the device against displacement, accidental or otherwise.

The partitions 10, 11 and 12 divide the frame into two horizontal compartments open on opposite sides so as to permit flow of water therethrough. In these compartments sets of adjustable stationary entrance guides 20 and 21 and sets of adjustable stationary discharge guides 30 and 31 are pivotally mounted. The terms "entrance" and "discharge" apply to the guides as shown in use in Figs. 1 and 3, but upon reversal of current flow the guides 30 and 31 become the entrance guides as in Figs. 2 and 6 while the guides 20 and 21 become discharge guides. The relative position of the upper and lower sets of guides is clearly shown in Fig. 1, and the parts in Figs. 1, 4 and 5 are positioned to coöperate with current flowing in the direction of the arrows a and a' . The entrance and discharge guides are each pivoted at one edge to the partitions or planes 10, 11 and 12, as indicated at 22 or 32, and are also each pivotally connected at the outer edge to links 23 or 33 by which each series of guides may be adjusted in position about the pivots 22 and 32. The links 23 and 33 are provided with extensions 24 and 34 having openings therein. They may be connected with any suitable shifting mechanism, or they may be moved manually to change the position of the stationary guides.

The flowing fluid as it passes between the entrance guides 20 and 21 engages a series of vanes 40 mounted for movement transversely of the current between the entrance and discharge guides. In the preferred form the vanes 40 are curved and are carried by link chains or belts 41 and 42 supported on sprockets 43, 44, 45 and 46 mounted in pairs on shafts 47 and 48. These shafts are rotatable in bearings 49 carried by the fixed frame of the machine, and power may be delivered from these rotated shafts in any convenient manner, as by a belt driven from the pulley 50 carried by the shaft 47.

Reference to Figs. 3 and 5 will show that the vanes 40 supported as described are movable in parallel runs in reverse directions adjacent and between the entrance and discharge guides previously described. The

parts are so arranged that fluid entering between the upper entrance guides 20 will move the vanes 40 in the direction of the arrow b in Fig. 3, while fluid entering between the lower guides 21 will move the 70 vanes in the direction of the arrow c in Fig. 3, these movements combining to give the entire system of vanes a continuous movement in a closed path, at the same time continuously rotating the shafts 47 and 48. 75

The discharge guides 30 and 31 extend practically in the line of the current and may be omitted when the machine is to be used in a river or in any position where the flow of current is always in the same direction. The use of these guides is essential, however, whenever a reversal of flow is to be expected. When the flow is reversed, the discharge guides 30 and 31 are moved by means of the links 33 to the positions shown 85 in Fig. 2, in which positions they will direct the fluid against the movable vanes 40, as indicated by the arrows x and x' in said figure. It will be evident that the fluid thus directed will cause the vanes to move in the same direction in which they moved before the direction of flow was reversed. At the same time the guides 20 and 21 which have now become discharge guides are moved to a position substantially in line with the line 90 of flow. Thus, by merely shifting the angular position of the entrance and discharge guides the machine may be instantly adapted to operate with the current flowing in the opposite direction, and the vanes 40 100 will be driven in the same direction under all conditions.

The links 23 and 33 may be connected in pairs by levers 35 pivoted at 36 whereby proper relative position of the coöoperating 105 guides is assured. The guides may be shifted, not only when the current is reversed, but also to control the speed of the motor, as any partial movement of the guides toward reverse position, without reverse of current, will reduce the speed, power and efficiency of the machine to a corresponding extent. Stop pins 51 may be provided in the fixed frame for limiting the movement of the guides, and for resisting 110 the pressure thereon when in entrance position.

While I have described the links 33 as adapted to be moved manually for shifting the guides to their entrance or discharge positions, it will be evident that this may be accomplished automatically by securing a guide or vane 52 to each link at such an angle that the pressure of the current flowing in either direction will shift the link 125 and the guides connected therewith to the corresponding entrance or discharge positions.

In order to resist the sidewise pressure of the current upon the vanes 40 a series of 130

grooved rolls 53 are mounted upon the fixed frame in position to engage the chains 41 and 42 at successive points during their travel from one supporting sprocket wheel to the other. These rolls are formed as double reverse cones and are thus adapted to position the chains and vanes vertically as well as to resist the sidewise pressure thereon.

10 In the modified form shown in Fig. 8, I provide rolls 54 at intervals upon the chains 41 and 42, these rolls coöperating with guide ways 55 secured to the fixed frame and engaging the rolls during their passage 15 through the upper and lower compartments. The guide ways 55 are each provided with a rib or projection 56 opposite the center of the roll 54 upon which the sidewise thrust is received with reduced friction.

20 In Fig. 9 I have shown an additional method of supporting the vanes 40 during their passage through the machine, by providing a series of rolls 60 projecting beyond the upper and lower edges of the vane, and 25 engaging fixed ways or tracks 61 secured to the partitions 10, 11 and 12. The rolls 60 are provided with flanges and thus engage the sides as well as the edges of the tracks 61. The rolls are mounted in reverse 30 pairs and thus resist sidewise thrust in either direction, as well as position the vanes vertically.

The partitions 10, 11 and 12, in addition to supporting the several parts of the mechanism, also perform an important function in dividing the current flow in horizontal planes into separate portions, so that the fluid entering the upper compartment may be diverted in one lateral direction, and the 40 fluid entering the lower compartment may be diverted in a substantially reverse direction. The middle partition is cut away at its ends to provide room for the sprocket wheels and the supporting shafts, and to 45 permit the vanes 40 to turn around the sprockets at the opposite ends of their path of travel.

It will be noted that the stationary guides when in normal entrance position gradually 50 decrease the cross sectional area of the passages through which the fluid approaches the vanes, whereby the velocity of flow is substantially increased. This increase of velocity, confined to the plane of the vanes 55 by the partitions 11, 12 and 13, enables me to attain high efficiency and great power in a machine of reasonable dimensions. It is found by experiment that the efficiency of the machine is noticeably increased when 60 the compartments are fully submerged. The machine will operate successfully but at a lower efficiency when either compartment is only partially submerged. My improved motor is thus adapted for use in tidal currents where it may be placed sub-

stantially upon the bottom, and it will be unaffected by the depth of the water flowing over it, or by changes in the depth of the water. Furthermore, it may be placed at the bottom of deep navigable rivers and 70 will work at its highest efficiency without in any way obstructing or interfering with navigation.

The word "transversely" as used in the claims is not limited to a direction at 90 75 degrees to the line of current, but indicates any direction forming a substantial angle thereto.

Having thus described my invention and certain modifications thereof, it will be evident that other changes and modifications can be made therein by those skilled in the art without departing from the spirit and scope of my invention as set forth in the claims, and I do not wish to be otherwise 80 limited to the details herein disclosed, but what I do claim is:—

1. A hydraulic current motor comprising a frame adapted to be fixed in the current, a plurality of guides arranged in series 90 transversely of the current and in superposed horizontal planes, means to secure each of said guides in said frame in a stationary position at an angle to the line of the current, a set of vanes movable in a 95 vertical plane transversely of the current and adjacent all of said stationary guides successively, connections between said vanes, and means for delivering power from said movable vanes, each portion of water which 100 passes through said guides acting once only on said vanes.

2. A hydraulic current motor comprising a frame adapted to be fixed in the current, two sets of guides arranged in parallel series 105 transversely of the current and in superposed horizontal planes, means to secure said guides in stationary position in said frame, the guides of one set being positioned at a certain angle to the line of the current and the guides of the second set being positioned at a reverse angle to the line of the current, a set of vanes movable in a closed path in opposite parallel runs transversely of the current and past said two sets of guides successively, connections between said vanes, and means whereby power may be delivered from said movable vanes, each portion of water which passes through said guides acting once only on said vanes.

3. A hydraulic current motor comprising a frame adapted to be fixed in the current, a set of entrance guides secured in said frame, a set of discharge guides secured in said frame and a set of vanes mounted for movement in a vertical plane transversely of the current between said two sets of guides, said entrance and discharge guides being closely adjacent said movable vanes on each side thereof and being adjustable in position,

whereby the direction of current flow may be reversed and the motor continue operative without change in the direction of movement of said vanes.

5. 4. A hydraulic current motor comprising a frame adapted to be fixed in the current, a set of entrance guides secured in said frame, a set of discharge guides secured in said frame in the same plane, and a set of 10 vanes mounted for movement transversely of the current between said two sets of guides and in a plane substantially at right angles to said first mentioned plane, said guides being closely adjacent said movable vanes on both sides thereof and being adjustable in position and being so shaped that the entrance guides when adjusted will be effective as discharge guides and the discharge guides when adjusted will be effective 15 as entrance guides upon reversal of the current flow, while the direction of the movement of the vanes remains unchanged.

5. 5. A hydraulic current motor comprising a frame adapted to be fixed in the current, 20 two sets of guides mounted therein in a single plane, a set of vanes movable between said two sets of guides in a plane normal to the plane of said guides, and means to adjust and secure said guides in said frame, 25 whereby either set of guides may be rendered effective as either entrance or discharge guides according to the direction of current flow.

5. 6. A hydraulic current motor comprising 30 a frame adapted to be fixed in the current and formed in upper and lower compartments positioned in superposed horizontal planes and open on opposite sides for the flow of water therethrough, a set of guides 35 in each compartment, means to secure said guides in reverse positions in said compartments, a set of vanes, movable connections for said vanes and means for supporting said connections whereby said vanes pass adjacent 40 the guides in one compartment in one direction and adjacent the guides in the second compartment in the opposite direction, and means to deliver power from said movable vanes.

5. 7. A hydraulic current motor comprising 45 a frame adapted to be fixed in the current and formed in upper and lower compartments open on opposite sides for the flow of water therethrough, said compartments being separated by a substantially continuous partition, a set of guides in each compartment, means to secure said guides in reverse positions in said compartments, a set of 50 vanes, connections for supporting and guiding said vanes, rotatable supports for said connections, whereby said vanes are movable in a closed path with parallel reverse runs adjacent said guides, and means to deliver power from said movable vanes.

5. 8. A hydraulic current motor comprising

a frame adapted to be fixed in the current and formed in upper and lower compartments open on opposite sides for the flow of water therethrough, a set of guides in each compartment, means to secure said guides in reverse positions in said compartments, a set of vanes movable in a vertical plane successively through said upper and lower compartments, connections between said vanes, sprockets for said vanes and connections, 70 horizontal shafts supporting said sprockets, and means to deliver power from said shafts.

9. A hydraulic current motor comprising a frame adapted to be fixed in the current and formed in upper and lower compartments open on opposite sides for the flow of water therethrough, entrance and discharge guides in each compartment, means to secure said guides in different positions whereby the functions of the entrance and discharge 85 guides may be readily reversed, a set of vanes, means to support said vanes for passage successively through said upper and lower compartments adjacent and between said entrance and discharge guides, rotatable supports for said means, and means to deliver power from said movable vanes and rotatable supports.

10. A hydraulic current motor comprising a frame adapted to be fixed in the current, 90 entrance guides fixed to said frame and disposed in a horizontal plane, a set of vanes, connections effective to support said vanes for movement in a vertical plane and for passage successively past said guides, rotatable supports for said means, and devices 100 for guiding said vanes during their movement past said guides from one rotatable support to another.

11. A hydraulic current motor comprising 105 a frame adapted to be fixed in the current, entrance guides fixed in said frame, a set of vanes, flexible means to support said vanes for passage past said guides, a set of rolls mounted on opposite edges of each vane and 110 fixed ways on said frame positioned for engagement by said rolls as said vanes pass said guides, whereby said vanes are held by said rolls and ways from displacement vertically or in the line of current.

12. A hydraulic current motor comprising 115 stationary guides disposed in superposed compartments having substantially continuous upper and lower inclosing members but open at opposite sides thereof, a series of 120 vanes movable in a vertical plane transversely of the current through said compartments successively, and means for adjusting said guides whereby said guides may be moved from their most efficient entrance position to their most efficient discharge position, thereby adapting said motor to a reversal of current flow, each portion of water 125 passing through said guides acting once only on said vanes.

13. A hydraulic current motor comprising stationary guides disposed in superposed compartments having substantially continuous upper and lower inclosing members but 5 open at opposite sides thereof, a series of vanes movable transversely of the current, through said compartments successively, and means for adjusting said guides at substantially reverse angles, said compartments dividing the flowing water into separate portions each effective to act upon said vanes once only and being freely discharged therefrom.

14. A hydraulic current motor comprising 15 upper and lower compartments, separated by a substantially continuous partition, reversely disposed guides in said compartments, and a series of vanes movable in a substantially vertical plane through said 20 compartments successively, said compartments dividing the flowing water into separate portions each effective to act upon said vanes once only.

15. A hydraulic current motor comprising 25 a set of guides effective to divert one portion of the flow at an angle to the line of current, a second superposed set of guides effective to divert a separate portion of the flow at a substantially reverse angle to the line of 30 current, and a set of vanes movable success-

sively in opposite runs past said two sets of guides, each portion of water acting once only on the vanes.

16. A hydraulic current motor comprising 35 a set of movable vanes, supporting members for said vanes whereby said vanes are movable in a closed path in opposite runs, and means for directing the flow against said movable vanes in the opposite runs at substantially reverse angles to the line of current, whereby each vane is acted upon by 40 different portions of the flowing water throughout the larger part of its circuit, each portion of water acting once only on said vanes and being freely discharged there- 45 from.

17. A hydraulic current motor comprising 50 a set of movable vanes and two sets of stationary guides, one set of said guides being positioned at each side of said movable vanes and closely adjacent thereto, and said guides being adjustably positioned whereby current flow in either of two opposite directions may be utilized with high efficiency to 55 carry the movable vanes in a single direction, and may be freely discharged after acting once only on said vanes.

In testimony whereof I have hereunto affixed my signature.

RALPH P. CLARKSON.
